UNITED STATES PATENT OFFICE.

VINCENT V. VEENSCHOTEN, OF ERIE, PENNSYLVANIA, ASSIGNOR TO NORTHERN EQUIPMENT COMPANY, OF ERIE, PENNSYLVANIA, A CORPORATION OF PENNSYLVANIA.

FLUID-PRESSURE CONTROLLER.

1,419,331.

Specification of Letters Patent. Patented June 13, 1922.

Application filed August 15, 1918. Serial No. 249,976.

To all whom it may concern:

Be it known that I, VINCENT V. VEENSCHOTEN, a citizen of the United States, residing at Erie, in the county of Erie and 5 State of Pennsylvania, have invented certain new and useful Improvements in Fluid-Pressure Controllers, of which the following is a specification.

This invention relates to devices adapted 10 to be operated by the pressure of fluids and particularly by the pressure of one fluid with relation to the pressure of some other fluid so that the operation depends upon the difference of pressure between the two fluids. 15 Although the device may be applied to many uses, the particular use which I have illustrated and described herein is a pump governor adapted to maintain a substantially constant excess pressure of the water dis- 20 charged by the pump with relation to the steam pressure which operates the pump. This form of governor is called a constant excess pressure governor.

On the accompanying drawings Fig. 1 is 25 an elevation, more or less diagrammatic, of a boiler system including a feed-water pump and governor therefor which embody the features of my invention. Fig. 2 is a central sectional view of the governor and of the 30 steam valve of the pump which is controlled thereby. Figs. 3 and 4, are other views of the governor and the valve.

As is well understood, a constant excess pressure pump governor controls the speed 35 of the pump by controlling the steam valve of the pump engine, the governor itself being operated by the relative pressures of the steam and of the water discharged by the pump. Steam generated in the boiler 5 passes through the pipe 6 to the valve 7 and thence to the engine 8. The pump 9, operated by the engine, pumps water through the pipe 10 to the boiler. The governor 11, which I have invented, comprises a steam 40 chamber 12 enclosed by suitable elastic cylinder 13. The cylinder, in this instance, comprises a cylindrical rubber surrounded by a coiled spring 14. The lower end of the cylinder is closed, and the upper end is 45 clamped between the disk 15 and the plate 16 by means of the tube 17 which is fixed to the disk. The lower end of the cylinder is supported by a disk 18 which also supports the coil 14, the lower end of the coil being 50 fixed to said disk 18 and the upper end be-

ing fixed to the casing. The tube 17 is operatively connected to the discharge pipe 10 of the pump by means of a pipe 19 so that the pressure of the feed water is effective on the interior of the cylinder 13. This 60 elastic cylinder is enclosed in a chamber 20 of the casing 21, and this chamber is operatively connected with the steam pipe 6 by means of a pipe 22, so that the elastic cylinder has the steam pressure effective on 65 its exterior, thus opposing the tendency of the water pressure within to expand the cylinder. The coil 14 prevents expansion of the cylinder transversely but allows longitudinal expansion, so that as the pressure 70 on the inside of the cylinder increases, in excess of the pressure on the outside, the disk 18, which is free to move, will be forced further away from the disk 15.

The governor 11 is operatively connected 75 with the steam valve 7 of the engine in any suitable manner. I prefer the following arrangement. A spindle 25 is journaled in the casing 21 of the controller and the casing 26 which is fixed to the casing of the 80 valve. One end of the spindle is connected to the disk 18 by means of an arm 27 and a rod 28, which are pivoted together. The other end of the spindle is connected to the valve plunger 29 of the valve 7 by means of 85 the arm 30 and the stem 31. As the arms are both fixed to the spindle, and movement of the disk 18 will cause a rotating movement of the spindle, and this, in turn will cause a longitudinal movement of the plunger. An arm 35, also fixed to the spindle, supports a weight 36 and the weight tends 90 to rotate the spindle so as to force the disk 18 upward against the pressure inside of the cylinder 13, thus assisting the steam pressure 95 outside of the cylinder in opposing the water pressure.

In practice, in normal operation, the pressure of the water in pipe 10 tends to force the disk 18 downwardly and thus to close 100 the valve 7 and shut down the pump; while the steam pressure, together with the weight 36, tend to open the valve. Thus, as usual with excess pressure governors, there is maintained a substantially uniform excess 105 pressure of the water with reference to the steam pressure, depending upon the effect of the weight 36 on the system. The weight may be shifted along the arm 35, so as to vary the magnitude of its effect. 110

I claim as my invention:

1. A pressure governor comprising a casing, a longitudinally elastic container enclosed in said casing with one of its ends 5 fixed to said casing, means for passing a fluid under pressure into said container, means for passing a fluid under pressure into said casing, operating means fixed to the free end of said container and a coil spring encircling 10 said container and fixed to said operating means.
2. A pressure governor comprising a casing, a longitudinally yielding container enclosed in said casing with one of its ends 15 fixed to said casing, means for passing into said container a fluid the pressure of which is to be governed, means for passing another fluid under pressure into said casing surrounding said container, operating means positioned against the free end of said container, and a coiled spring enclosing said 20 container, the end of said spring adjacent the fixed end of said container being fixed to

said casing, and the other end of said spring being fixed to said operating means.

25

3. A controller comprising a casing, a yielding cylinder fixed by one end within said casing, operating means positioned against the free end of said cylinder, a spring coil enclosing said cylinder and tending to prevent longitudinal extension thereof, means for passing a fluid under pressure into said cylinder whereby a fluid tending to elongate said cylinder may be passed therein, means for passing a fluid under pressure into said casing whereby a fluid tending to shorten said cylinder may be passed into said casing, and other adjustable means arranged so as to tend to vary the length of said cylinder.
